ATTY'S

UNITED STATES PATENT OFFICE.

HENRY MARTINI, OF PAWNEE, ILLINOIS, ASSIGNOR, BY DIRECT AND MESNE ASSIGNMENTS,
OF ONE-HALF TO HIRAM M. YOUNG, OF JEWETT, TEXAS.

SAFETY-CATCH FOR MINE-CAGES.

No. 907,835.

Specification of Letters Patent.

Patented Dec. 29, 1908.

Application filed August 1, 1907. Serial No. 386,655.

To all whom it may concern:

Be it known that I, HENRY MARTINI, a citizen of the United States, and resident of Pawnee, Sangamon county, Illinois, have invented certain new and useful Improvements in Safety-Catches for Mine-Cages, of which the following is a specification containing a full, clear, and exact description, reference being had to the accompanying drawings, 10 forming a part hereof.

My invention relates to a safety catch for mine cages, my object being to construct a simple, inexpensive, and automatic arrangement, which will instantly act and stop the 15 descent of a mine cage should the hoisting cables thereof break, thus preventing loss of life and property due to the accidental dropping of the cage.

To the above purposes, my invention consists in certain novel features of construction and arrangement of parts, which will be hereinafter more fully set forth, pointed out in the claims, and illustrated in the accompanying drawings, in which:

25 Figure 1 is a side elevation of the cage in position between the vertical guides, which are arranged on opposite sides of the mine shaft; Fig. 2 is a vertical section taken on the line 2—2 of Fig. 1; Fig. 3 is an enlarged 30 detail section taken on the line 3—3 of Fig. 2; Fig. 4 is a transverse section taken on the line 4—4 of Fig. 3; Fig. 5 is a perspective view of a block made use of in the ends of the head beam of the cage; Fig. 6 is a perspective 35 view of a sliding block made use of in the ends of the head beam, and which sliding block engages with the stops formed on the guides for the cage; Fig. 7 is an elevation of a portion of one of the guides, and showing 40 the manner in which the ends of the sections are joined; Fig. 8 is a vertical section taken on the line 8—8 of Fig. 7; Fig. 9 is a perspective view of one of the brackets such as is 45 used in the cage guides, and with which the sliding blocks engage.

Referring by numerals to the accompanying drawings:—1 designates the vertical guides for the cage, which are in the form of channel bars, and which are vertically disposed on opposite sides of the shaft, and said guides being made in sections, with the lower ends of each section provided with a tongue 2, which overlaps the web of the upper end of the adjacent section, and the overlapping 50 ends being bolted or riveted together. Rig-

idly fixed in any suitable manner to the webs of the guides 1, at equal distances apart, are brackets 3, which form stops against which engage the outer ends of the sliding blocks carried by the head beam of the cage. The 60 body of the cage comprises a platform 4, of any suitable construction, which is carried by the lower ends of upright bars 5, and the upper ends of said upright bars being rigidly fixed in any suitable manner to the head 65 beam of the cage. This head beam comprises a pair of I-beams 6, arranged parallel with one another, a slight distance apart, and the ends of said I-beams being connected in any suitable manner to the upper ends of 70 the bars 5. The flanges of these I-beams terminate just inside the flanges of the guides 1, and the vertical webs of said I-beams are extended a short distance, as designated by 75 7, so as to occupy positions on the sides of the guides 1, thus providing means for guiding the upper end of the cage.

Brackets 8 are bolted to the sides of the platform 4, and extend outward on the sides of the guides 1, thus providing means for 80 guiding the lower end of the cage. The inside lower flanges of the I-beams 6 are cut away at the ends of said beams, and detachably positioned on the under sides of the beams of these cut away points are plates 9, 85 provided with integral blocks 10, which extend upward between the vertical webs of said I-beams. Arranged to slide longitudinally on top of these blocks 10, and beneath the inner flanges on the tops of said 90 beams, are blocks 11, provided on their outer ends with the integral lugs 12, which are adapted to engage on top of the brackets 3 when said blocks 11 are moved outward; and formed integral with the opposite ends 95 of the blocks 11 are the vertically disposed arms 13, which project upward between the inner flanges at the tops of the I-beams 6.

Plates 14 are rigidly fixed on top of and below the I-beams 6, at the centers thereof, 100 and arranged for vertical movement through said plates is a rod 15, the lower end of which is provided with a nut 16, the upper end being provided with a perforated head 17. Located on the rod 15, above the top plate 105 14, is a retractile coil spring 18, the lower end of which is fixed to said top plate 14, and the upper end being fixed to the rod 15, adjacent the head 17. Pivotaly connected to the head 17 are the upper ends of links 19, the 110

lower outer ends being pivotally connected to the upper ends of the arms 13. Connected to the perforated head 17 is the lower end of a chain 20, the upper end of which is secured to a ring 21, and carried by said ring are the upper ends of chains 22, the lower ends of which are connected in any suitable manner to the upper ends of the upright bars 5.

10 The hoisting cables for the cage are connected to the ring 21, and when the cage is properly suspended in the shaft between the guides 1, the rod 15 is pulled upward to its limit of movement, thus expanding the retractile coil spring 18, and the blocks 11 are held at their inward limit of movement, with the outer ends of the lugs 12 entirely free from the guides 1 and brackets 3 fixed thereto. With the parts thus 15 positioned, the cage is free to move vertically between the guides, with the parts 7 and 8 traveling on the side faces of said guides.

Should the hoisting cables break, the power stored in the retractile coil spring 18 20 will instantly act to move the rod 15 downward; and, as a result, the lower ends of the links 19 are moved outward, thus moving the blocks 11 outward between the I-beams 6 and over the blocks 10; and the ends of 25 the lugs 12 carried by said blocks 11 are moved between the flanges of the channel bar guides 1 and into engagement with a pair of the brackets 3, thus instantly stopping the descent of the cage.

30 Should the blocks 11 or the parts carried thereby become broken or worn while in use, they can readily be detached by removing the blocks 10 located in the ends of the head beam of the cage.

35 An apparatus of my improved construction comprises a minimum number of parts, can be cheaply manufactured, owing to the fact that nearly all the parts required are of ordinary commercial shapes, such as are 40

easily obtained in the open market; and 45 the guides for the cage, being made in sections, can be readily extended downward as the depth of the shaft is increased.

I claim:—

1. The combination with vertically disposed guides and stops arranged thereon, of a cage operating between said guides comprising a pair of I-beams rigidly fixed to one another and arranged at the upper end of the cage, the vertical flanges of which I-beams are extended so as to engage the side faces of the guides, blocks removably fixed to the under sides of the I-beams at the ends thereof, sliding blocks arranged on the fixed blocks, the outer ends of which sliding 55 blocks engage with the stops on the guides, and means connected to the sliding blocks whereby the same are moved outward when the hoisting cable of the cage is broken.

2. The combination with a pair of vertical guides and stops arranged thereon, of a cage arranged to operate between said guides comprising a pair of I-beams rigidly fixed to one another and arranged between the guides at the upper end of the cage, blocks 60 detachably fixed to the under sides of the I-beams at the ends thereof, blocks arranged to slide on the fixed blocks, the outer ends of the sliding blocks being adapted to engage with the stops on the guides, a spring actuated rod arranged for operation between the I-beams, a connection between said rod and the hoisting cables of the cage, and links arranged between the upper end of the rod and 65 the sliding blocks.

80 In testimony whereof, I have signed my name to this specification, in presence of two subscribing witnesses.

HENRY MARTINI.
